UNITED STATES PATENT OFFICE.

ROBERT BEAM, OF BATTLE CREEK, MICHIGAN.

CURTAIN-SHADE FIXTURE.

1,319,025.

Specification of Letters Patent.

Patented Oct. 14, 1919.

Application filed March 17, 1919. Serial No. 283,251.

To all whom it may concern:

Be it known that I, ROBERT BEAM, a citizen of the United States, residing at Battle Creek, in the county of Calhoun and State 5 of Michigan, have invented certain new and useful Improvements in Curtain-Shade Fixtures, of which the following description, taken in connection with the accompanying drawing, forms a specification.

10 The present invention relates to curtain shade fixtures and contemplates means for attaching the same to window casings without injury to the same, by the elimination of screws, tacks, etc.

15 A characteristic feature of the present invention lies in means for holding the same between the window casings by the use of right and left handed screw bearings at the ends of the shade roller container.

20 Among other objects of the invention is to provide an article of the class whereby a shade roller may be easily and securely placed in a window without the aid of screws or nails and without disfiguring or in 25 any manner injuring the window casing; whereby the same will admit of drapery attachments in a simple and effective manner; whereby the fixture will be neat and tasty in design, stable in attachment, easy to place 30 and detach, simple in construction and economical to manufacture. These and other objects and advantages will be more clearly set forth in the following specification, shown in the accompanying drawing, and 35 defined in the appended claims.

In the drawing forming a part of this specification, Figure 1 is a perspective view of my improved curtain fixture attached to the casing of a window.

40 Fig. 2 is a broken and longitudinal section of the fixture between the casing of a window.

Fig. 3 is a detail cross section with a curtain fixture impressed against a window 45 strip.

Fig. 4 is a detail cross section with a curtain fixture impressed against a window strip, the shade container being turned in a manner preparatory to rolling the same for 50 forcing its end bearings against the window strips to hold the fixture in position.

Fig. 5 is a detail section of the curtain container tube.

55 Fig. 6 is a perspective view of the shade roller bearing.

Fig. 7 is a perspective view of a curtain fixture.

In the drawings, like marks of reference refer to corresponding or equivalent parts throughout the views in which A represents 60 a window casing; B, a window shade; C, a curtain rod; D, the shade roller barrel or container.

The shade roller container is a metallic casing having a longitudinal slot 1 its entire 65 length, and when in normal or operative position opens downwardly or rearward and downwardly for the purpose of permitting the shade B to be fully operated or wound and unwound from its roll 2 over a window. 70 At either end of the barrel or container dished bearings, as 3 and 4, are placed. One of the bearings is provided with a round gudgeon hole 5 for receiving the rolling gudgeon 6 of the shade roll, the opposite 75 end-bearing 4 being formed with an elongated slot (not shown) for receiving the shank of the gudgeon of the spring, customary in shade rollers. The bearings are formed with indrawn bosses, as 7, which 80 when the bearings are placed over the ends of the shade container barrel D extend within the slot 1 and prevent said bearings from turning on said barrel. The bearings 3 and 4 are further formed with exteriorly formed 85 screw-threads one of which is right handed and the other left handed, for a purpose herein-after set forth.

Screw-threaded on each of the bearings 3 and 4 spanner collars 8 and 9 are adapted to 90 be placed and fitted on the ends of said collars, rubber or other pads 10 employed. The office of the pads is to avoid scratching, marring or otherwise injuring the window casing or window strips in putting up the 95 shade fixture.

Where curtains are used in connection with the shade roller fixture a right angularly formed metallic support E is provided on the wing 11 on which the curtain rod 100 bracket 12 is seated. As shown, the wing 11 is curved or bent inwardly along its lower edge, and when in position on a window casing bears against said casing and forms an open space between the casing and the 105 body of the wing, within which space a finger or hook 13 of the curtain rod bracket 12 may freely pass.

The bracket 12 where it bears against the wing 11 has a broadened downward exten- 110

sion abutting said wing and in connection with the finger 13 forms a slot striding the wing and permitting said bracket to be slid along the wing as occasion may require to 5 allow a limited range of adjustment in the hanging of a curtain.

In operation, a shade roller having been inserted into its container D, the bearings 3 and 4 together with their spanner collars 8 10 and 9, respectively, are placed over the ends of said container and the collars turned sufficiently on said bearings to snugly admit the assemblage of parts, including the pads 10 on the ends of said collars, between the 15 window strips of a window casing with the slot or opening 1 of the container in a position toward the window top, or upwardly as shown in Fig. 4. The container is thence 20 forwardly turned so that its slot will open from its lower or lower and rear side, a process through the medium of the right and left handed screw-threads of the parts, as set forth, which will force the spanner 25 collars 8 and 9 together with the pads 10 outwardly against the window casing and sustain the parts in operative position.

When it is desired to use the curtain hanging brackets as aforesaid, the brackets are inserted between the ends of the spanner 30 collars and the casing or casing strips of a window, and the same process conducted as though said curtain brackets were not used, it being understood that the cushion pads be employed between the casing and the curtain 35 fixture.

From the foregoing description taken in connection with the drawing, a more extended description of the operation and advantages of my improved curtain shade fixture 40 is believed not necessary.

Having, therefore, set forth my invention, what I claim as new and desire to secure by Letters Patent, is:—

1. In a curtain shade fixture, the combination with a longitudinally slotted shade container, dished bearings placed over either end of said container, said bearings having lugs extending within the slot of said container, said bearings formed exteriorly with 45 right and left handed screw threads, interiorly screw-threaded spanner collars screw-threaded on said dished bearings, one of said 50

bearings having a roller gudgeon hole, the opposite bearing having a spring shank bearing hole and pads on the ends of said collars, substantially as set forth. 55

2. In a curtain shade fixture, the combination with a longitudinally slotted shade container, internally dished shade bearings placed over either end of said container, 60 means to prevent said bearings from turning on said container, said bearings having right and left handed screw-threaded exteriors, respectively, and spanner collars screw-threaded to said bearings whereby 65 said shade fixture may be extended to impress the side casings of a window opening, substantially as and for the purpose set forth.

3. In a curtain shade fixture, the combination with a longitudinally slotted shade container, dished bearings placed over either end of said container, said bearings having lugs extending within the slot of said container, said bearings formed exteriorly with 75 right and left handed screw-threads, respectively, spanner collars screw-threaded on to said bearings and pliable pads placed over the ends of said spanner collars, substantially as and for the purpose set forth. 80

4. In a curtain shade fixture, the combination of a longitudinally-slotted shade container, dished bearings placed over the ends of said container, means for preventing said bearings from rolling on said container, said 85 bearings having right and left handed screw-threads, respectively, exteriorly formed thereon, and spanner collars screw-threaded onto said bearings.

5. In a curtain shade fixture, in combination, a longitudinally-slotted curtain container, dished bearings placed over either end of said container, one of said bearings being screw-threaded and prevented from rolling on said container, a spanner collar 95 screw-threaded onto said screw-threaded bearing, and pads placed over the ends of said assemblage of parts to engage the side casings of a window. 90

ROBERT BEAM.
